CLAIM

The ornamental design for a shooting rest bag, as shown and described.

DESCRIPTION

FIG. 1 is a top rear right-side perspective view of a shooting rest bag showing my new design.

FIG. 2 is a bottom perspective view of the shooting rest bag of FIG. 1.

FIG. 3 is another top perspective view of the shooting rest bag of FIG. 1.

FIG. 4 is another bottom perspective view of the shooting rest bag of FIG. 1.

FIG. 5 is a top perspective view of the shooting rest bag of FIG. 1.

FIG. 6 is a bottom perspective view of the shooting rest bag of FIG. 1.

FIG. 7 is a rear perspective view of the shooting rest bag of FIG. 1.

FIG. 8 is a front perspective view of the shooting rest bag of FIG. 1.

FIG. 9 is a left perspective view of the shooting rest bag of FIG. 1.

FIG. 10 is a right perspective view of the shooting rest bag of FIG. 1; and,

FIG. 11 is a top rear right-side perspective view of the shooting rest bag of FIG. 1 showing the shooting rest bag supporting a firearm on a fence rail.

The evenly spaced broken lines in FIGS. 1-10 show portions of the shooting rest bag that form no part of the claimed design. The additional broken line structure in FIG. 11 shows environmental structure that forms no part of the claimed design.

1 Claim, 5 Drawing Sheets
